DESIGN FOR A COMBINED CHAIN AND SKIRT GUARD FOR BICYCLES

John R. Morgan, Oak Park, Ill., assignor to Sears,
Roebuck and Co., Chicago, Ill., a corporation
of New York

Application April 30, 1936, Serial No. 62,386

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Combined Chain and Skirt Guard
for Bicycles, of which the following is a specifici-
cation, reference being had to the accompany-
ing drawing, forming a part thereof.

Fig. 1 is a side view,

Fig. 2 is a view similar to Fig. 1, but showing
the opposite side, and

Fig. 3 is a top plan view of a combined chain
and skirt guard for bicycles embodying my new
design.

I claim:

The ornamental design for a combined chain
and skirt guard for bicycles, as shown.

JOHN R. MORGAN.
